PUMP BASE

Linus E. Russell, Springfield, Ohio, assignor to Peters & Russell, Inc., Springfield, Ohio, a corporation of Ohio

Filed Sept. 8, 1958, Ser. No. 759,740

1 Claim. (Cl. 103—218)

This invention relates to base constructions for stirrup pumps and like devices, and especially to a formed stirrup-like member of especial utility in this connection.

The object of the invention is to simplify the construction as well as the means and mode of operation of pump bases, whereby such bases may not only be economically manufactured, but will be more efficient and satisfactory in use, adaptable to wide variety of applications, and be unlikely to get out of order.

A further object of the invention is to provide a formed sheet metal base for stirrup pumps and like devices, it being contemplated in this regard to obviate the relatively heavy devices of the prior art having a screw threaded or other fixed association with the pump cylinder.

Another object of the invention is to present a formed sheet metal base as described providing in and of itself an area of containment for the lower end of the cylinder, with adequate access to the interior thereof, as well as abutment means to accept upward thrusts delivered by pulling motions upon the cylinder, such thrusts being absorbed by the foot of the operator applied to the stirrup base.

A further object of the invention is to provide a generally new stirrup-like base as described incorporating clamping devices and readily adapted for attachment to any detachment from the pump cylinder.

A further object of the invention is to provide a pump base possessing the advantageous structural features, the inherent meritorious characteristics and the mode of operation herein mentioned.

With the above and other incidental objects in view as will more fully appear in the specification, the invention intended to be protected by Letters Patent consists of the features of construction, the parts and combinations thereof, and the mode of operation as hereinafter described or illustrated in the accompanying drawings, or their equivalents.

Referring to the accompanying drawing wherein is shown one but obviously not necessarily the only form of embodiment of the invention:

Fig. 1 is a view in perspective of a base for stirrup pumps and the like in accordance with the illustrated embodiment of the invention, shown mounted upon the lower end of a cylindrical hand pump;

Fig. 2 is a view of the structure of Fig. 1 in side elevation; and

Fig. 3 is a top plan view of the base of Figs. 1 and 2, pump parts being omitted.

Like parts are indicated by similar characters of reference throughout the several views.

Referring to the drawing, a pump of the kind to which a base in accordance with the present invention is applied comprises a cylinder 10 on the lower end of which is an enlargement 11 which may be either integral with the cylinder or a separate part attached thereto. A boss 12 on the enlargement 11 defines an opening to the interior of the cylinder and serves as the inlet or the outlet

2

depending upon the use of the pump. At the point of juncture of the cylinder 10 with the enlargement 11 there is defined an approximately radial projection or shoulder 13 which is circular in shape in conformance with the cylindrical configuration of the cylinder 10 and enlargement 11.

The base structure is initially a strip of sheet metal which is bent about longitudinally spaced apart transverse lines 14 and 15 to achieve an approximately U-shaped configuration made up of a planar tread or rest portion 16 and upstanding arms 17 and 18 extend upward to define a tubular clamp, abutment means and an area of containment as before mentioned, and it will be understood that the respective arms are identically formed and complement one another in the achieving of the desired conformations and configurations.

For a short distance above the transverse lines 14 and 15 the arms 17 and 18 incline at a gradual angle toward the vertical axis of the rest portion 16. At a point 19 this angle of inclination becomes more acute and marginal portions of the arms progress in a line to a point 21 where the respective arms are adjacent to the vertical axis of the rest portion 16, on opposite sides thereof, and so in adjacent relation to one another. From point 21, such marginal edges rise an appreciable extent in longitudinal, parallel relation to one another to define flanges 22. The respective flanges on both marginal edges are perforated to receive clamping devices 23.

Intermediate their marginal edges, and starting from point 19 to the top of the flanges 22, the arms 17 and 18 are deformed outwardly. In the area of the flanges 22, this deformation takes the shape of a semi-cylindrical recess 25 in each arm, the recesses being of longitudinal extent, paralleling the flanges 22, and further complementing one another to define in conjunction with the flanges 22 a tubular clamp to receive and to be adapted to the external configuration of the pump cylinder 10. Thus, as indicated in Fig. 1, the upper extremities of the arms 17 and 18 are formed with complementary semi-cylindrical recesses adapted to conform this part of the base structure to the configuration of the cylinder 10 so that upon tightening of the clamping devices or fasteners 23 the base will be frictionally held to the cylinder. The clamp portion of the base is applied to the cylinder 10 immediately above the enlargement 11 which places the latter in position between the arms 17 and 18 and it will be understood that this will be accomplished in a manner to permit the boss 12 to project outwardly between the arms for the extension of a hose line therefrom. The intermediate portions of the arms 17 and 18, beneath the tubular clamp, are also deformed in the shape of a circular recess of longitudinal extent but in this instance the recess is of a progressive depth varying from a minimum depth at point 19 to a maximum depth at the base 55 of the tubular clamp. This is accomplished by continuing the center line of each arm 17 and 18 in the angle of inclination which the arms have initially, and laterally curving the material of the arms to the marginal edges which lie in and define the more acute angle as described.

60 The result is, as indicated, to define an inner recessed area 26 in each arm 17 and 18, with the pair of arms cooperating to produce what may be considered an area of containment since it conforms itself approximately to curvature of the enlargement 11 and interfits with such curvature to obviate twisting or tilting movements of the cylinder 10 relatively to the base. Moreover, at its point of maximum depth, the circular recess 26 is connected to the base of the tubular clamp, or more particularly to the lower end of a semi-cylindrical portion 25, by an approximately radial shoulder 27 which overlies the shoulder 13 and forms an abutment means on the interior of the base to limit withdrawal of the cylinder relatively

to the base in an installed position of the parts. The shoulders 27 have an arcuate shape and complement one another in achieving an abutment means conforming to the circular configuration of the shoulder 13.

When mounted to the cylinder 10, therefore, a base in accordance with the present invention becomes a secure part of the pump facilitating and enabling its use as a stirrup pump. It is however, readily detached from the pump, merely by loosening or removing the devices 23, and, as is evident, is of a simple and inexpensive construction being made of a single piece of sheet metal and by a simple stamping or like manufacturing procedure.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect, and the invention is therefore claimed in any of its forms or modifications within the legitimate and valid scope of the appended claim.

Having thus described my invention I claim:

A pump having a cylinder with an external enlarge-

ment on the exterior thereof adjacent the bottom thereof, said external enlargement forming a shoulder on the pump cylinder, an opening in the bottom of the enlargement, a base for said pump comprising a one-piece formed sheet having a planar rest portion and side arms that raise from the ends of said rest portion, said arms being inclined towards a normal axis for said rest portion in first a gradual and then a steeper angularity, portions of the arms of the steeper angularity abuttingly engaging the shoulder formed by the upper surface of the external enlargement on the pump cylinder thereby forming a holding device to prevent the upward movement of the cylinder relative to the base on the upper stroke of the pump, the marginal portion of said arms at their extremities thereof being reversely bent to occupy planes adjacent one another and parallel to the vertical axis of the pump cylinder, said marginal portions of said arms being each correspondingly perforated to accept receiving devices, portions of the arms between the margins thereof being inwardly deformed to define at their extremities a tubular clamp, said base forming an area of containment below the bottom of the pump cylinder and the opening therein.
